UNITED STATES PATENT OFFICE.

OSCAR D. KLEINSTEUBER, OF MILWAUKEE, WISCONSIN, ASSIGNOR OF FORTY ONE-HUNDREDTHS TO HUGO A. KLEINSTEUBER, OF MILWAUKEE, WISCONSIN.

MUNICIPAL SERVICE POST.

Application filed November 9, 1922. Serial No. 599,868.

To all whom it may concern:

Be it known that I, OSCAR D. KLEINSTEUBER, a citizen of the United States, and resident of Milwaukee, in the county of Milwaukee and State of Wisconsin, have invented certain new and useful Improvements in Municipal Service Posts; and I do hereby declare that the following is a full, clear, and exact description thereof.

10 The invention relates to improvements in municipal service posts of the type set forth in my Patent #1,165,420.

The entire device is of such nature as to be readily assembled within a post, such as 15 illustrated in the patent. A substantially rectangular base member has a pair of rectangular supports extending upwardly therefrom and inwardly from adjacent corners with a slight inclination towards each 20 other. A rectangular panel cooperates with these supports to form a complete compartment, housing a fire alarm box and completely partitioning it from the other features of the device.

25 An object of this construction is the utilizing of the space in a most economical manner. The panel is provided with means for securing it in place in such manner as to make it readily detachable, the construction 30 facilitating an examination of the electric wires. The bottom of the panel is received in a trough U-shaped in cross section, which extends from one support to another and is effective to prevent looseness or rattling of 35 the panel.

An important feature of this construction is the simplicity of manufacture and the extreme ease of assembly of parts. The trough structure is of such nature also as to prevent a beating in of rain into the other compartments. Outwardly directed to a side of 40 the square base member, are a pair of parallel troughs extending perpendicularly from the aforesaid trough and U-shaped in 45 cross section. These troughs are adapted to receive a pair of panels, one of which supports a police signal and telephone apparatus, while the other carries telephone apparatus for the use of municipal officials and 50 employees.

A bracket is provided for gripping the tops of the three panels in their assembled

position and holding them rigid. Each of these panels operates to form a distinct compartment, acting as a partition. 55

An important feature of the structure is the ready assembly of the various panels into position and the extreme simplicity of the parts cooperating to that effect.

Again, the structure is adapted to pre- 60 clude all rattling and looseness of parts.

Other objects and advantages will appear as the description proceeds.

Reference is had to the accompanying 65 drawings, in which

Figure 1 is a plan view of the invention.

Figure 2 is a cross section on the line 2—2 of Figure 1, and

Figure 3 is a cross section on the line 3—3 of Figure 1. 70

Base member 10 is substantially square but cut away at the corners. Rectangular supports 11—11' are made rigid therewith by L shaped brackets 12, secured by suitable means, as bolt 13. The supports extend in 75 vertical planes and are directed inwardly somewhat towards each other. A panel 14 rectangular in shape is adapted to cooperate with supports 11 with which it contacts to form a complete compartment. 80

A trough 15, U-shaped in cross section, receives the bottom of panel 14 and prevents movement thereof in the plane of the base member 10 and supports 11—11' have deformations 16—16' in close contactual relationship with panel 14. From these deformations lugs 17—17' having openings 18—18', extend and panel 14 is provided with bolts or other suitable means 19—19' adapted to be received in the upper portion of openings 18—18' respectively, and moved downwardly therein to hold the panel in rigid position, the heads 20—20' of the bolts being incapable of transverse movement through the lower part of openings 18—18'. 95

A fire alarm box 21 is suitably secured to the front of the panel 14. A bracket is provided for gripping the top of panel 14. It has an elongated horizontal portion 22, having a downwardly directed front flange 23 and three downwardly directed rear flanges 24. Arms 25—25' are rearwardly extended from horizontal portion 22 and provided with flanges 26—26', 27—27'. A panel 28

is adapted to be gripped at its top by flanges 26—26', and its bottom is received in trough 29 secured rigid with base member 10 by means of pins 30. Panel 31 similarly is adapted to be received in corresponding flanges on the bracket, and in a similar trough 32. Panel 31 supports telephone apparatus 33 for the use of municipal officials and employees, and panel 28 supports a police signal and telephone apparatus 34. In assembling the members in position, panel 14 may be positioned in trough 15 and the heads 20—21 engaged in openings 18—18'. Panels 28 and 31 may then be placed in troughs 29 and 32 with their ends abutting against panel 14 and the bracket may be placed in position with its downwardly projected flanges holding the various parts rigid.

20 While a preferred embodiment of the invention has been illustrated and described, it is to be understood that the present invention is not confined to such specific embodiment, but may be otherwise embodied within 25 in the spirit of the invention and the scope of the following claims, and it will further

be understood that a substantial range of equivalence is contemplated.

I claim:

20 A device for insertion into the compartment of a municipal service post, said device having transverse and longitudinal panel units provided with signalling devices, a base having a transverse trough for receiving said transverse panel unit and 35 having a pair of troughs extending outwardly with reference to said first mentioned trough and adapted to receive the longitudinal panel units with one vertical edge of each abutting a face of said transverse panel, means for releasably locking said transverse panel in place, and a spider bracket having a channel for receiving the upper edge of said transverse panel and 40 having means for holding the upper end of 45 each of said longitudinal panels.

In testimony that I claim the foregoing I have hereunto set my hand at Milwaukee, in the county of Milwaukee and State of Wisconsin.

OSCAR D. KLEINSTEUBER.
